UNITED STATES PATENT OFFICE.

FELIX LINDNER, OF LUDWIGSHAFEN-ON-THE-RHINE, GERMANY, ASSIGNOR TO
BADISCHE ANILIN & SODA FABRIK, OF LUDWIGSHAFEN-ON-THE-RHINE, GERMANY,
A CORPORATION OF BADEN.

DECOLORIZING GLYCERIN.

1,089,775.

Specification of Letters Patent. Patented Mar. 10, 1914.

No Drawing.

Application filed April 26, 1910. Serial No. 557,724.

To all whom it may concern:

Be it known that I, FELIX LINDNER, a subject of the King of Saxony, residing at Ludwigshafen - on - the - Rhine, Germany, have invented new and useful Improvements in Decolorizing Glycerin, of which the following is a specification.

The usually employed method of rendering glycerin colorless, or nearly so, is to heat it with animal charcoal. I have now discovered that the hydrosulfites and the formaldehyde sulfoxylates can be used for the purpose of decolorizing glycerin, and that these afford advantages over the use of animal charcoal for the purpose. Difficultly soluble, or insoluble, salts of hydro-sulfurous acid and of formaldehyde sulf-oxylic acid are particularly useful for the purpose of this invention, as, if these be used, the ash contents of the glycerin will not be increased to any great extent.

In carrying out my invention the glycerin can be treated with the hydrosulfite, or with the formaldehyde sulfoxylate, either with the glycerin in solution, or not, although the solutions containing glycerin, such as are obtained during the manufacture of soap by the saponification of fats and oils with caustic alkali, are not well adapted to be conveniently directly decolorized by the use of hydrosulfites, or formaldehyde sulfoxylates, according to this invention. The said hydrosulfites, or formaldehyde sulfoxylates, can, however, be very conveniently employed to decolorize the glycerin obtained by splitting up fats and oils by heating them with water under pressure and in the presence of an agent such as zinc, zinc oxid, or magnesium oxid, and in this case the hydrosulfite, or formaldehyde sulfoxylate, can be added during the splitting up of the fats and oils, and then both the glycerin and the fatty acid become decolorized to a greater or lesser extent.

Among the compounds which can be used for decolorizing glycerin according to this invention I mention sodium hydrosulfite with a constitution probably corresponding to the formula $Na_2S_2O_4$, sodium formaldehyde sulfoxylate with a composition probably corresponding to $NaHSO_2CH_2O$, and basic zinc formaldehyde sulfoxylate with a

constitution probably corresponding to the formula $ZnSO_2CH_2O$, or a complicated anhydrid thereof. For the purpose of this invention, I regard hydrosulfites as equivalent to formaldehyde sulfoxylates.

The following examples will serve to illustrate how my invention can be carried into practical effect, but the invention is not confined to these examples. The parts are by weight.

Example 1: Introduce half a part of decrolin (basic zinc formaldehyde sulfoxylate) into one hundred parts of dark brown crude glycerin which has to some extent been purified in the usual manner by means of a salt of iron, or of aluminium, and which is maintained at a temperature of from ninety, to one hundred, degrees centigrade. After a short time a light yellow product is obtained. The way in which the decrolin is used can be varied to suit different processes of manufacture, for instance, it can be added to the crude glycerin solution, or it can be added while the solution is being evaporated *in vacuo*, or it can be added to the concentrated glycerin. The quantity of decrolin added should vary according to the color of the glycerin to be treated.

Example 2: Add a mixture of zinc dust, or magnesium oxid, and decrolin, containing about two and a half parts of decrolin, to a mixture of two thousand five hundred parts of cotton seed oil with water, and heat the whole in an autoclave in the manner generally employed for splitting up cotton seed oil. The glycerin solution thus obtained is colorless, or practically colorless, whereas if no decrolin is added, it is yellow. The addition of decrolin, moreover, improves the purity of the fatty acid obtained.

Now what I claim is:—

The decolorization of glycerin by treating it (either in solution, or not) with a formaldehyde sulfoxylate, substantially as hereinbefore described.

In testimony whereof I have hereunto set my hand in the presence of two subscribing witnesses.

FELIX LINDNER.

Witnesses:

ERNEST F. EHREHARDT,
W. W. SCHMIDT.
